7 Claims. (Cl. 260—681.5)

This invention relates to the separation and concentration of isomeric diolefins and particularly to the concentration and isolation of a cis-diolefin.

Piperylene (1,3-pentadiene) is a first in the homologous series of conjugated diolefins to exist in two geometrical isomeric forms. Since these two isomers possess different details of chemical activity in some reactions, it is desirable to be able to concentrate the individual forms.

An object of this invention is to separate cis-piperylene from trans-piperylene.

Another object of this invention is to separate cis-piperylene from other hydrocarbon compounds particularly those present in a cracked petroleum fraction.

According to this invention the conjugated diolefins present in hydrocarbon fractions are preferably first concentrated to substantially complete exclusion of other types of hydrocarbons. This concentration is preferably carried out by the use of a process which does not promote isomerization of cis-diolefins to trans-diolefins. Such a process is in the use of solid cuprous salts as extractants. The initial diolefin fraction is preferably derived from a high temperature source such as the cracking of gas oil or the thermal or catalytic dehydrohalogenation of the higher dihaloalkanes. In any case the purified conjugated diolefin mixture is submitted to reaction under appropriate conditions with a reagent capable of undergoing the so-called Diels-Alder condensation with conjugated diolefins, whereby the trans-diolefin reacts substantially completely to form unsaturated cyclic compounds; however, it has been found that the cis-isomer reacts slowly, if at all, with these reagents and therefore remains in substantially pure form as a recoverable residual hydrocarbon.

This invention relates particularly to the separation of pure cis-piperylene from its mixtures with transpiperylene. It also relates particularly to the use of maleic anhydride as the Diels-Alder condensing agent, but it has been shown that the process is applicable to higher diolefins and to other condensing agents.

The two isomers of piperylene have a molecular structural difference which may be represented in one plane as:

Now since the Diels-Alder condensation with maleic anhydride involves a closure to form a six-membered ring, an explanation of the differ-

ence in reactivities of the cis- and trans-isomers of the diolefin might lie in the interference of the protruding methyl group of the cis-isomer in the ring closure. Thus, the trans-form reacts

5 readily,

Trans-piperylene + maleic anhydride → methyltetrahydrophthalic anhydride

15 while the cis- fails to give any appreciable condensation.

15

With regard to the conjugated diolefins containing more than five carbons, the invention is 25 applicable to compounds having the following general structure and also capable of existing in the form of two geometrical isomers:

25

30 where R_1 is alkyl or aryl, but preferably methyl, R_2 and R_3 are hydrogen, alkyl or aryl. The geometrical isomer inactive to Diels-Alder condensation is the form in which the ethenyl group 35 is cis with respect to R_1 and which we arbitrarily term the cis-isomer.

Example I

30 A fraction of hydrocarbons derived from the steam cracking of gas oil at very high temperatures, boiling between 37° and 45° C., and substantially free of cyclopentadiene was treated with cuprous salts in an appropriate manner 40 whereby piperylene was concentrated in substantially pure form as a mixture of its cis- and trans-isomers. The high purity of this fraction was vouched for by its index of refraction and by its reaction with two moles of hydrogen per mole.

The purified piperylene was then vaporized into 50 a stream of hydrogen and the resulting mixture was dispersed and caused to pass through a body of molten maleic anhydride maintained at 100° C., after which the gas was freed of entrained material and passed through a condenser at -78° C. 55 Thereby the unreacted piperylene was condensed and collected. The collected residue had most of the chemical properties of piperylene but differed in that it was virtually unreactive with Diels-Alder condensation reagents, particularly maleic anhydride. The properties of the orig-

local biphenyls and various substituted biphenyls are summarized in the following table:

	Geplante verbundene Festungen	Geplante verbundene Festungen
1. Normale abwehrfeste mit 10% Zulage	41.000	41.000
2. Linie der erforderlichen Festungen	1.000.000	1.000.000
3. Max. der verhältnismässig möglichen Zulage	100%	100%
4. (gekennzeichnet) 1. (gekennzeichnet) 2. (gekennzeichnet) 3.	35.800	35.800
5. (abzüglich) 1. (abzüglich) 2. (abzüglich) 3.	35.800	35.800

4. A second descriptio binig p[ro]p[ter]it et c[on]sp[ec]tus p[er]p[re]f[er]endis exco[n]s[er]tis
tratis ex h[ab]itu obiectis mundis et c[on]sp[ec]tus exco[n]s[er]tis tratis
p[er]p[re]f[er]endis ex h[ab]itu obiectis mundis.

Example 11

Sample 4111

1. This is the first step of the K-means process. It is a process of selecting initial cluster centers. In this step, we randomly select k data points from the dataset as initial cluster centers. These centers are represented by the green dots in the scatter plot.
